UNITED STATES PATENT OFFICE.

ZENUS C. ANGEVINE, OF LONG BEACH, CALIFORNIA.

COLLAPSIBLE BED.

1,246,218.

Specification of Letters Patent. Patented Nov. 13, 1917.

Application filed October 8, 1914. Serial No. 865,767.

To all whom it may concern:

Be it known that I, ZENUS C. ANGEVINE, a citizen of Canada, residing at Long Beach, in the county of Los Angeles and State of California, have invented new and useful Improvements in Collapsible Beds, of which the following is a specification.

This invention relates to improvements in collapsible beds of the character broadly 10 claimed in Letters Patent of the United States, No. 1,101,481, granted to me June 23, 1914, and comprehends a combination of bed frame elements, pivotal connecting elements for the frame elements, a bed spring frame 15 relatively movable to collapse into a limited space and rigidly spaced bed post sections carried by the mattress frame and interlocking with the collapsing bed post sections in the extended position to form a rigid bedstead of neat, original and ornamental appearance, that can be readily and conveniently collapsed into compact form for 20 storage and transportation without detaching any of the parts.

25 The invention also comprises various novel features, elements and combinations as will more fully appear from the drawings herewith and the subjoined detail description.

30 It is an object of the invention to so relate the frame elements, the corner posts, the interlocking mechanism, and the connecting braces, that the bedstead shall be more attractive in appearance when the bed 35 is open, that the bedstead shall hold the bedding and mattress securely when the bedstead is in the collapsed position, and that the collapsed bedstead may be stored in minimized space.

40 A further object of the invention is to provide a bedstead, capable in the collapsed position of being moved through a doorway of the ordinary height and width and that may in the collapsed position be concealed 45 in a recess in the wall.

A further object of the invention is to so provide for counterbalancing the weight of the bed springs and bedding, that the attendant may fold the bed to collapsed position 50 with greater ease.

A further object of the invention is to provide a compensating adjustment to balance the bed springs with variable weight of mattress and bedding.

55 A further object of the invention is to minimize weight in a collapsible bed. This

is accomplished by making the connecting braces and the bed spring frame serve as the collapsing mechanism, and arranging the pivotal connections to shift in position as 60 the bed is folded, so that the line of direction of the mattress frame, mattress and bedding is through the pivotal axis of said frame; and said frame will stand vertically 65 edgewise when the bed is collapsed.

A still further object is to provide improved means to hold the bedstead securely in open position.

While the elements shown and described are well adapted to serve the purposes for 70 which they are intended, it is to be understood that the invention is not limited to the precise construction exhibited herein, but may include variations and modifications which may fall within the scope of the 75 appended claims, the essence of the invention comprising a bedstead having sections relatively movable to a collapsed position, and a tilting spring frame coöperating with the bedstead sections to change and secure 80 the bed in either open or collapsed position, the combination and arrangement of the elements being ornamental rather than machine-like in appearance.

Other objects and advantages may appear 85 from the subjoined detail description and the adaptation of the invention shown in the drawings.

The accompanying drawings illustrate the 90 invention.

Figure 1 is a perspective of a collapsible bed constructed in accordance with this invention with the parts in open or use position.

Fig. 2 is an end elevation of the bed 95 shown in Fig. 1. Broken lines indicate partly closed and fully closed positions.

Fig. 3 is a perspective detail of a post bracket having a latching element, the bracket being detached from its corner post. 100

Fig. 4 is a perspective detail of the latch bracket that coöperates with the post bracket to hold the mattress frame from tilting and to secure the bed in open position, the brackets being detached from the mattress frame. 105

Fig. 5 is a perspective detail of a mattress frame hanger bracket detached from the adjustable element of one of the posts. 110

Fig. 6 is a perspective detail illustrating the lower bracket for the tilting link.

Fig. 7 is a fragmental sectional detail

illustrating a central bed frame post with lifting springs, mattress frame connection, and adjusting means to change the tension of the lifting springs in accordance with the 5 weight of mattress and bedding.

Fig. 8 is fragmental perspective of the mattress frame with details of the locking and releasing means therefor.

Fig. 9 is a fragmental sectional detail of 10 the mattress frame locking means.

Fig. 10 is an elevation of the mattress frame hanger together with the cam for assisting to raise the mattress frame as it is tilted.

15 Fig. 11 is a fragmental sectional detail in elevation of a locking end section of the bed frame with the interlocking mechanism therefor. The collapsed position of said end section is shown in broken lines.

20 Fig. 12 is a fragmental detail on line $\alpha^1\alpha^2$, Fig. 11.

Fig. 13 is a sectional detail of a movable bushing element within a post of the locking end section to release the interlocking 25 mechanism.

Fig. 14 is a plan of the top of the corner post when the end locking section is collapsed as indicated by dotted lines in Fig. 11.

30 Fig. 15 is a perspective of the interlocking bushing detached.

Fig. 16 is a fragmental detail in section of the interlocking mechanism.

Fig. 17 is an elevation of the trigger carrying collar of the interlocking mechanism.

Fig. 18 is a plan of collar shown in Fig. 17.

Assuming the invention to be embodied as illustrated, the bedstead central frame section 1 has a longitudinally disposed bar 2, holding in opposed relation uprights or non-rising central posts 3, within which the central telescoping members 4 operate; the rear side section 5 has a longitudinal bar 6, holding in opposed relation non-rising 45 corner posts 7, within which the side telescoping members 8 operate; the front side section 9 has a longitudinal bar 10 connecting non-rising posts 11 within which telescoping members 12 operate. An upper side 50 bar 13 maintains the parallelism of the bed posts.

Sleeves 14 slide in sets respectively upon bars 2, 6, 10. Lazy tongs 15, which have pivotal connection respectively with fixed 55 brackets 16, 17, and sliding sleeves 14, maintain the parallelism of the bed sections.

Additional lazy tongs 18 which have pivotal connection respectively with brackets 19, 20, 21 fixed to non-rising posts 3, 7, 60 11, and pivotal connection with brackets 22, 23, fixed to rising post members 4, 8, 12, are provided, the four sets of tongs insuring proper alinement of the posts in the collapsing movement. The lazy tongs connections 65 15 are horizontal, that is to say, their pivots

a are vertical, and the lazy tongs 18 are vertical, that is to say, their pivots *b* are horizontal. By the arrangement shown each side frame is connected to the center frame having the vertical posts 3 by the lazy tongs 2 and which as 15 are horizontal with vertical pivots, and the other two, 18, are vertical with horizontal pivots *b*. By this arrangement and construction perfect alinement and parallelism between the frames 70 while the bedstead is expanded and also while it is collapsed are maintained.

A mattress or bed spring frame 24, consisting of end bars 25, preferably of angle iron, side bars 26, holding the end bars in 80 opposed relation, and depending brackets 27, 28, connecting the side bars with the end bars, is pivotally mounted at its middle relative to the central bed frame section 1, the end bars 25 being provided with hangers 29 85 swinging upon pivotal pins 30 fixed to brackets 22 on sliding section 4 of posts 3. The central posts 3 are provided with trunnion brackets 20 carrying trunnions 31 on which are mounted rollers 32, the rollers 32 90 being adapted to engage with curved cams 33 formed as guide ways in parts integral with hangers 29. The bed spring frame may therefore be tilted on its longitudinal axis to a vertical position; its path of movement 95 being determined by rollers 32, following the guide ways 33.

Locking means for securing the spring frame 24 in open position are provided comprising sliding bolts 34 mounted in brackets 100 28, the bolts 34 passing through holes 35 provided in brackets 19. Brackets 19, fixed to corner posts 7, have angularly disposed strike faces 36, which automatically actuate the bolts as the frame 24 is turned to the open 105 position. To withdraw the sliding bolts from their locking positions, they are provided with rods 37, connected at one end to the sliding bolts and at the other end to a tumbler 38, the tumbler 38 being fixed to a 110 rotating rod 39 provided with an operating handle 40. A spiral spring 41 having one end fixed to rod 39 and its opposite end fixed to side bar 26, serves to actuate the rod and tumbler to throw sliding bolts 34 into the 115 locking position, and a fixed collar 42 on each bolt limits the movement of the sliding bolts. The opposite side of frames 24 is supported in the open position by brackets 27 dropping into engagement with 120 brackets 21 which are fixed to corner posts 11 of the bed frame.

Brackets 27, 28, have dovetail tenons 43, 44 which slip into corresponding sockets 45 in brackets 19, 21 when the bed spring frame 125 approaches the horizontal position.

Additional means for locking the bedstead in open position comprise frames or end locking sections 46, having supplementary posts 47, and tubular cross bars 48, 130

49, hold posts 47 in opposed relation. These frames constitute post-engaging means pivotally mounted on the mattress frame to hold the mattress frame in horizontal position and the posts apart, and also form the 5 head and foot boards of the bed, and are pivotally mounted on the mattress frame 24, and fold into parallelism with frame 24 in the closed position of the bed. These frames 10 constitute post-engaging means which as shown in Fig. 11 may form a rigid joint to prevent collapsing as will more fully appear in the following description.

A latch in the form of a tapered plunger 15 50 in each supplementary post is adapted to engage with a corresponding socket 51 fixed in each of post sections 8, 12. Each plunger 50 is held in engagement with a socket 51 by a spring 52 interposed between 20 a collar 53 fixed to the plunger, and a bushing 54 fixed within the post 47. Each plunger 50 has a hollow piston 55 having a slot 56 in the wall thereof having teeth 57 extending in the slot and forming a rack. A 25 rotating rod 58 having pinions 59 engaging with racks 57 extends through each of the cross bars 48, and the rod and pinions are adapted to operate the pistons and plungers simultaneously in their respective supplementary frames. To disengage plunger 50 30 a knurled rotating handle 60 is provided in the top of each of posts 47, said handle 60 being secured against end movement by a pin 61 projecting from the walls of the post 35 into an annular groove 62 of said rotating handle 60. Miter gears 63 transmit motion from handle 60 to rods 58, and thus by turning handle 60 the plungers may be withdrawn against the tension of springs 52.

40 Each of the plungers 50 is provided with a trigger 64, pivotally secured to collar 53, the trigger being actuated by a spring 65 to engage with a detent 66, secured to the wall of post 47. The plungers 50 may therefore be withdrawn from their corresponding 45 sockets 51, thereby releasing supplementary posts 47 and permitting frames 46 to be folded upon the bed spring frame 24. Each of posts 47 is provided with a bracket 67 50 having pivotal connection with a bracket 67' secured to frame 24, the brackets 67 being shaped to allow the frames 46 to fold upon and secure the mattress and bedding (not shown) in the closed position of the 55 bed.

Means for releasing plungers 50 consist of releasing rods 68, one of which is slidably mounted in and co-axial with each plunger, and projects from the end thereof, 60 the inner end of the releasing rod bearing against the trigger 64. Sockets 51 have slots 69 through which ends 70 of the releasing rods pass as the frames 46 are folded upon frame 24; each slot having a rocker 65 71 actuated by a spring 71' and swinging

outward as the frame begins its folding movement. The rockers are rounded at their upper ends and actuate the releasing rods 68 which in turn actuate triggers 64 and thereby release plungers 50 as the frames 46 approach the open position.

A rigid link 72 pivotally secured to a lug 73 on bracket 16 and pivoted to a lug 74 on hanger bracket 29 cooperates with the cam way 33 and roller 32 to collapse the bed 75 frame as the spring frame 24 is tilted; the link 72 causing the axis of frame 24 to rise as the mattress or bed-spring frame approaches the edgewise vertical position. Means for adjusting the tension of springs 80 75 consist of plungers 76 each having a flattened toothed upper end 77 and rotating members 78 fixed against end movement by pins 79 and mounted in the upper ends of members 4, the members 78 85 being threaded to engage with ends 77 of plungers 76. Ends 77 slide through corresponding slots 80 in pins 30. By turning members 78 the tension of springs 75 may be adjusted in accordance with the weight of 90 the moving parts of the bed.

To counterbalance the weight of the bed spring frame and whatever weight of mattress and bedding may be carried thereon, posts 3 have interior coiled springs 75 which 95 actuate plungers 76, connected with the telescoping members 4. The springs may be adjusted so that the spring frame will slowly rise automatically to the vertical position when bolts 34 are released from locking engagement with brackets 19.

Assuming the bed to be in the open position as shown in Figs. 1, 2 the method of changing to the collapsible position may be understood from the following description. 105 First, the knurled handles 60 are rotated until the plungers 50 are released. End frames 46 are then swung over into parallelism with the mattress frame as indicated by dotted lines in Figs. 2 and 11 to a position approximately parallel with spring frames 24. Second, the handle 40 is turned thereby releasing locking bolts 34 whereupon frame 24 under action of the lifting springs 75 will be slowly turned from horizontal to vertical 115 position. The tilting of frame 24 will cause members 4, 8 and 12 to move upward relative to posts 3, 7 and 11 respectively, thus spreading and thereby shortening the four sets of lazy tongs which consequently draw 120 the outer bed frame sections toward the central section all of which is effected simultaneously with the tilting movement of frame 24. The lazy tongs operating in both vertical and horizontal planes preserve the 125 alignment of the bed frame sections in the collapsing movement and collapsed position of the bed.

To open the bed the edge of the mattress frame will be grasped by the attendant and 130

5 brought to horizontal position, the operative parts above described operating in a manner obvious from the foregoing, and when the mattress frame reaches the locked 10 horizontal position the locking end sections 15 will be moved up into locking position shown in Figs. 1, 2 and 11.

In the open position of the bed, the frames 46 form respectively the head and 10 foot of the bed, and interlock with the outer bed frame sections 1, 9 forming a rigid bedstead which cannot collapse without having the locking means released by the attendant.

I claim:

15 1. A collapsible bed having vertically disposed telescoping corner posts, side bars connecting opposed corner posts one way, an intermediate frame having telescoping posts, lazy tong connections between the telescoping members of the corner posts and the telescoping posts, springs for retracting the lazy tongs, a mattress frame pivotally mounted at its 20 middle on the intermediate frame and post 25 engaging means on the mattress frame to hold the mattress frame in horizontal position and the posts apart.

2. A collapsible bed having vertically disposed telescoping corner posts, side bars 30 connecting opposed corner posts one way, an intermediate frame having telescoping posts, lazy tong connections between the telescoping members of the corner posts and the telescoping members of the intermediate 35 posts, springs for retracting the lazy tongs, the side bars and the intermediate frame being parallel; sleeves sliding on the side bars and intermediate frame, and second lazy tongs connecting the lower telescoping 40 members and the sleeves.

3. A collapsible bed having telescoping corner posts, outer side bars rigidly connecting the corner posts one way to form side frames, an intermediate frame having 45 intermediate telescoping posts and having an intermediate bar parallel with the outer side bars, sleeves sliding upon the outer side bars and upon the intermediate bar, vertical lazy tongs connecting the telescoping members of the side frames to the telescoping 50 members of the intermediate frame and to each other, horizontal lazy tongs connecting the ends of the side frames to the end of the intermediate frame and connecting said 55 sleeves and springs for retracting the lazy tongs and counter-balancing.

4. A collapsible bed having a bedstead frame comprising sections connected together and relatively movable to a collapsed 60 position, a tilting frame, and interlocking sections pivoted to the tilting frame and adapted to fold thereon and also adapted to lock said relatively movable sections in the open position.

65 5. A collapsible bed having a bedstead

formed of sections relatively movable to a collapsed position, a mattress frame having pivotal connection with the bedstead, and link and cam connecting means connecting the frame and a section of the bedstead whereby the bedstead sections are collapsed coincident with the tilting of the mattress frame.

6. A collapsible bed having a bedstead 75 formed of sections relatively movable to a collapsed position, a mattress frame having a longitudinally pivotal connection with the bedstead, and end sections having a transverse pivotal connection with the mattress frame and adapted to interlock with the bedstead sections in the open position of the bed.

7. A collapsible bed having intermediate 85 and side telescoping bedstead sections relatively movable to a collapsed position, a mattress frame having pivotal connection with the intermediate section of the bedstead, lazy tong connecting means whereby the bedstead sections are collapsed and telescoped coincident with the tilting of the bed 90 spring frame, and a link pivoted to the bedstead frame and to the mattress frame to cause the telescoping movement of the bedstead sections as the bedstead sections are moved toward and from collapsed position.

8. A collapsible bed comprising a frame 95 having telescoping bedstead sections relatively movable to and from a collapsed position; said bedstead sections comprising an intermediate section and outer sections; said sections consisting of upright posts, connecting bars holding the posts in opposed end relation, telescoping members within the upright posts, and a spring to extend the telescoping members, a plurality of lazy 100 tong bars interposed between said intermediate section and the outer sections and connecting adjacent posts and telescoping members together, a mattress frame pivoted to the telescoping members of the central 105 posts, and links pivoted to the central posts, and to the mattress frame, said spring being adapted to operate to lift the telescoping members to operate the lazy tongs to collapse the bedstead and tilt the mattress 110 frame to a vertical position.

9. The combination with a tiltable mattress frame, of side frames and an intermediate frame having telescoping bed posts, continuous vertical lazy tong connections between the telescoping members of transversely aligned bed posts, an expansive spring 115 between the telescoping members of one of the posts, continuous horizontal lazy tong connections parallel with the vertical connections, and connections between the mattress frame and the vertical lazy tongs 120 whereby the side frames move toward each other when the mattress frame moves to upright position and vice versa, the force of 125 130

said springs serving to counterbalance the parts.

10. A collapsible bed comprising a frame having telescoping bedstead sections relatively movable to a collapsed position, a mattress frame having pivotal connection with the bedstead, lazy tong connecting means to move the bedstead sections to and from each other and to maintain the parallelism of the bedstead sections in the collapsing movement, trunnions fixed to certain of the telescoping bedstead sections, rollers mounted on the trunnions, and curved cam ways fixed to the mattress frame 15 and engaging with said rollers, thereby collapsing the bedstead coincident with the tilting of the mattress frame.

11. A collapsible bed comprising three longitudinally disposed bed frame sections, 20 three pairs of members telescoping relative to the bed frame sections, lazy tong connections between the bed frame sections and telescoping members to telescope the members simultaneously and to maintain the 25 alignment of the bedstead sections in the collapsing movement, a mattress frame having pivotal connection with one pair of said telescoping members, a pair of rollers carried by one of said bed frame sections, and 30 curved cam ways fixed to the mattress frame and engaging with said rollers, said cam ways having a spiral curve thereby causing the mattress frame and the telescoping members to raise as the mattress frame is tilted 35 to close the bed.

12. In a collapsible bed, an intermediate frame having rigid intermediate bedstead posts, intermediate telescoping members in the rigid posts, a mattress frame pivoted to 40 the intermediate telescoping members, side frames having rigid side bedstead posts, side telescoping members in the rigid side posts, vertical lazy tongs connecting the rigid 45 posts and connecting the telescoping members, so that the mattress frame is raised when the side frames move toward each other and vice versa.

13. In a collapsible bed, an intermediate frame having rigid intermediate bedstead 50 posts, intermediate telescoping members in the rigid posts, a mattress frame pivoted to the intermediate telescoping members, side frames having rigid side bedstead posts, side telescoping members in the rigid side 55 posts, vertical lazy tongs connecting the rigid posts and connecting the telescoping members, so that the mattress frame is raised when the side frames move toward each other and vice versa, and expansion 60 springs between the intermediate rigid posts and their telescoping members, the tension of the springs tending to contract the lazy tongs and raise the mattress frame.

14. In a collapsible bed, an intermediate 65 frame having rigid intermediate bedstead

posts, intermediate telescoping members in the rigid posts, a mattress frame pivoted to the intermediate telescoping members, side frames having rigid side bedstead posts, side telescoping members in the rigid side 70 posts, vertical lazy tongs connecting the rigid posts and connecting the telescoping members, so that the mattress frame is raised when the side frames move toward each other and vice versa, and connections between the mattress frame and the lazy tongs whereby tilting the mattress frame contracts the lazy tongs.

15. In a collapsible bed, an intermediate frame having rigid intermediate bedstead 80 posts, intermediate telescoping members in the rigid posts, a mattress frame pivoted to the intermediate telescoping members, side frames having rigid side bedstead posts, side telescoping members in the rigid side 85 posts, vertical lazy tongs connecting the rigid posts and connecting the telescoping members, so that the mattress frame is raised when the side frames move toward each other and vice versa, and expansion springs 90 between the intermediate rigid posts and their telescoping members, the tension of the springs tending to contract the lazy tongs and raise the mattress frame, and connections between the mattress frame and the 95 lazy tongs whereby the mattress frame is tilted when the lazy tongs are contracted.

16. In a collapsible bed, an intermediate frame having rigid intermediate bedstead posts, intermediate telescoping members in 100 the rigid posts, a mattress frame pivoted to the intermediate telescoping members, side frames having rigid side bedstead posts, side telescoping members in the rigid side 105 posts, vertical lazy tongs connecting the rigid posts and connecting the telescoping members, so that the mattress frame is raised when the side frames move toward each other and vice versa, and head and foot boards foldably mounted on the mattress 110 frame and adapted to interlock with the corner telescoping members to hold the bed open.

17. In a collapsible bed, an intermediate frame having rigid intermediate bedstead 115 posts, intermediate telescoping members in the rigid posts, a mattress frame pivoted to the intermediate telescoping members, side frames having rigid side bedstead posts, side telescoping members in the rigid side 120 posts, vertical lazy tongs connecting the rigid posts and connecting the telescoping members, so that the mattress frame is raised when the side frames move toward each other and vice versa, and expansion 125 springs between the intermediate rigid posts and their telescoping members, the tension of the springs tending to contract the lazy tongs and raise the mattress frame, and head and foot boards foldably mounted on the 130

- mattress frame and adapted to interlock with the corner telescoping members to hold the bed open. 60
18. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and connections between the mattress frame and the lazy tongs whereby tilting the mattress frame contracts the lazy tongs, and head and foot boards foldably mounted on the mattress frame and adapted to interlock with the corner telescoping members to hold the bed open. 65
19. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and expansion springs between the intermediate rigid posts and their telescoping members, the tension of the springs tending to contract the lazy tongs and raise the mattress frame, trunnions and rollers carried by the central rigid posts, and means forming eccentric guideways carried by the mattress frame, said rollers operating in said guideways, so that the mattress frame will tilt to an upright position as the lazy tongs contract and vice versa. 70
20. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and expansion springs between the intermediate rigid posts and their telescoping members, the tension of the springs tending to contract the lazy tongs and raise the mattress frame, trunnions and rollers carried by the central rigid posts, and means forming eccentric guideways carried by the mattress frame, said rollers operating in said guideways, so that the mattress frame will tilt to an upright position as the lazy tongs contract and vice versa. 75
21. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and expansion springs between the intermediate rigid posts and their telescoping members, the tension of the springs tending to contract the lazy tongs and raise the mattress frame, trunnions and rollers carried by the central rigid posts, and means forming eccentric guideways carried by the mattress frame, said rollers operating in said guideways, so that the mattress frame will tilt to an upright position as the lazy tongs contract and vice versa. 80
22. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and head and foot boards foldably mounted on the mattress frame and adapted to interlock with the corner telescoping members to hold the bed open, trunnions and rollers carried by the central rigid posts, and means forming eccentric guideways carried by the mattress frame, said rollers operating in said guideways, so that the mattress frame will tilt to an upright position as the lazy tongs contract and vice versa. 85
23. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and expansion springs between the intermediate rigid posts and their telescoping members, the tension of the springs tending to contract the lazy tongs and raise the mattress frame, and connections between the mattress frame and the lazy tongs whereby the mattress frame is tilted when the lazy tongs are contracted, and head and foot boards foldably mounted on the mattress frame and adapted to interlock with the corner telescoping members to hold the bed open. 90
24. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, and expansion springs between the intermediate rigid posts and their telescoping members, the tension of the springs tending to contract the lazy tongs and raise the mattress frame, and connections between the mattress frame and the lazy tongs whereby the mattress frame is tilted when the lazy tongs are contracted, and head and foot boards foldably mounted on the mattress frame and adapted to interlock with the corner telescoping members to hold the bed open. 95
25. In a collapsible bed, an intermediate frame having rigid intermediate bedstead posts, intermediate telescoping members in the rigid posts, a mattress frame pivoted to the intermediate telescoping members, side frames having rigid side bedstead posts, side telescoping members in the rigid side posts, vertical lazy tongs connecting the rigid posts and connecting the telescoping members, so that the mattress frame is raised when the side frames move toward each other and vice versa, trunnions and rollers carried by the central rigid posts, and means forming eccentric guideways carried by the mattress frame, said rollers operating in said guideways, so that the mattress frame will tilt to an upright position as the lazy tongs contract and vice versa. 100

In testimony whereof, I have hereunto set my hand at Los Angeles, California, this 3d day of October, 1914.

ZENUS C. ANGEVINE.

In the presence of—

JAMES R. TOWNSEND,
FREDERIC M. KEENEY.
